UNITED STATES PATENT OFFICE.

GEORGE E. WILSON AND WILLIAM J. FRAWLEY, OF STILLWATER,
MINNESOTA.

REHEATER.

No. 847,713.

Specification of Letters Patent. Patented March 19, 1907.

Application filed February 6, 1906. Serial No. 299,803.

To all whom it may concern:

Be it known that we, GEORGE E. WILSON and WILLIAM J. FRAWLEY, both of Stillwater, Washington county, Minnesota, have invented 5 certain new and useful Improvements in Reheaters for Compound Engines, of which the following is a specification.

Our invention relates to steam super-heaters, and particularly to one designed 10 for use in connection with a cross-compound traction-engine.

In the operation of a compound engine considerable annoyance and difficulty has been experienced because of the presence of 15 wet steam in the low-pressure cylinder due to the rapid condensation of the exhaust in passing from the high to the low pressure cylinder. By partial expansion in the high-pressure cylinder the steam loses some of its 20 heat and elasticity or becomes wet and entering the low-pressure cylinder in this condition materially reduces the power and efficiency of the engine.

The object, therefore, of our invention is 25 to provide means for drying or reheating the exhaust-steam of the high-pressure cylinder before it enters the low-pressure cylinder.

The invention consists, generally, in arranging a reheater in the boiler fire-box between the high and low pressure cylinders. 30

Further, the invention consists in various constructions and combinations all as hereinafter described, and particularly pointed out in the claims.

35 In the accompanying drawings, forming part of this specification, Figure 1 is a transverse vertical sectional view of a traction-engine fire-box and a cross-compound engine mounted thereon. Fig. 2 is a side elevation 40 of the fire-box, showing the position of the reheater therein. Fig. 3 is a plan view of the reheater removed from the fire-box.

In the drawing, 2 represents the boiler fire-box and 3 and 4 the high and low pressure cylinders of the engine. 5 and 6 represent the steam-chests, respectively, of said cylinders, and 7 is a jacket inclosing the cylinders and forming the subject-matter of a 45 companion application for United States Letters Patent of even date herewith, Serial No. 289,802.

The high-pressure cylinder has an exhaust-passage 8, leading to a three-way valve 9, which communicates with a pipe 10,

leading to the engine-stack, and with a pipe 55 11, which is extended down beside and through the upper wall of the fire-box. A corresponding pipe 12 is extended through the opposite fire-box wall and leads to the steam-chest 6 of the low-pressure cylinder. 60 Between the open ends of the pipes 11 and 12 and extending transversely in the upper part of the fire-box is a hollow casting 13, preferably curved slightly from end to end and having extensions 14 at each end, to which 65 the open ends of the pipes 11 and 12 are attached. The casting 13 presents a broad heating-surface to the flames in the fire-box, and the exhaust from the high-pressure cylinder passing down through the pipe 11 and 70 into the reheater casting will be reheated and become thoroughly dry and regain a very large proportion, if not all, of its normal expansive power. In other words, the wet steam from the high-pressure exhaust will be 75 reheated and delivered to the low-pressure cylinder in a condition which will insure the highest efficiency and power of the engine.

We do not claim, broadly, the idea of reheating steam; but we believe it to be entirely novel to reheat the exhaust of a cross-compound traction-engine by locating the reheater in the engine fire-box and compelling the exhaust-steam to pass therethrough on its way from the high to the low pressure cylinder. 80 We do not wish in this application, however, to confine ourselves to the particular shape or size of the reheater casting or its location in the upper part of the fire-box, as 85 its form may be varied and its position in the fire-box may be changed without materially altering its functions or the result obtained.

The use of this reheater will insure the delivery of the exhaust-steam to the low-pressure cylinder in a very dry state, and prevent, 90 to a considerable degree, the accumulation of water in the low-pressure cylinder and the necessity of opening the cylinder-cocks during the initial operation of the engine. 95

We claim as our invention— 100

1. The combination, with a traction-engine boiler, of a compound engine located above said boiler and comprising high and low pressure cylinders having steam-chests and valves therefor, said high-pressure cylinder having an exhaust-passage and a pipe 105 communicating with said passage, said pipe having an inwardly-turned extension at its

lower end projecting through the wall of said boiler into the fire-box, and the steam-chest of said low-pressure cylinder having a pipe communicating therewith at its upper end and provided with an inwardly-turned extension at its lower end also projecting through the wall of said boiler into the fire-box, and a receptacle located in the upper part of said fire-box and presenting a broad 5 heating-surface to the flames and having a steam-passage with angled extensions at each end connected with the inwardly-turned extensions of said pipes, the walls of said extensions being opposite the open ends 10 of said pipes whereby the exhaust-steam from said high-pressure cylinder will be retarded as it passes through said receptacle and reheated and dried before its delivery to said low-pressure cylinder, substantially as 15 described.

2. The combination, with a traction-engine boiler, of a compound engine arranged over said boiler and comprising high and low pressure cylinders having steam-chests and 20 valves therefor, said high-pressure cylinder having a downwardly-extending exhaust-passage 8 and a valve 9 and pipe 11 commu- 25

nicating with said passage through said valve, said pipe 11 having an inwardly-turned extension at its lower end projecting through the wall of said boiler into the fire-box and the steam-chest of said low-pressure cylinder having a pipe 12 communicating therewith at its upper end and provided with an inwardly-turned extension at its lower end also projecting through the wall of said boiler into the fire-box and a hollow casting located in the upper part of said fire-box and presenting a broad heating-surface to the flames in said box and having holes in its ends wherein the inwardly-turned extensions of said pipes 11 and 12 are inserted whereby the exhaust-steam from said high-pressure cylinder will be reheated and dried before its delivery to said low-pressure cylinder, substantially as described.

In witness whereof we have hereunto set our hands this 30th day of January, 1906.

GEORGE E. WILSON.
WILLIAM J. FRAWLEY.
